Homer G. Mahan,

Geo. P. Kinney
ATTORNEY

UNITED STATES PATENT OFFICE.

HOMER G. MAHAN, OF WILLIAMSBURG, KENTUCKY.

DUMP CAR.

Application filed April 2, 1928. Serial No. 266,661.

This invention relates to dump cars, and more particularly to cars of this character which are used in the mining industry for transporting coal, ore, etc., and has for its object to provide in a manner as hereinafter set forth:

A dump car wherein the doors which constitute the floor of the car, will be automatically released for the purpose of discharging the cargo, after which said doors will be automatically closed and latched.

Further objects of the invention are to provide in a manner as hereinafter set forth, a dump car of the aforementioned character which is simple in construction, efficient in its use strong, durable, and which may be manufactured at low cost.

In the drawings which illustrate this invention—

20 Figure 1 is a side elevation of the dump car in accordance with this invention.

Figure 2 is a like view looking towards the opposite side of the car.

Figure 3 is an end elevation showing the doors closed.

Figure 4 is a plan view.

Figure 5 is a longitudinal sectional view on the line 5—5 of Figure 4.

Figure 6 is a transverse sectional view 30 taken on the line 6—6 of Figure 4, and

Figure 7 is a detail view, partly in section, of the door latching mechanism.

Referring to the drawings in detail, the reference character 1 designates generally 35 the body of the car and comprises a pair of vertical side walls 2 having outwardly flared top portions 3. The side walls are connected at their opposite ends by vertical end walls 4. The body 1 is provided with a supporting frame comprising a pair of side beams 5 connected at their opposite ends by the end beams 6. The supporting frame entirely surrounds the lower portion of the body.

The bottom, or floor of the body, is formed 45 of a pair of longitudinally extending doors 7, hingedly secured at the outer edges thereof to the side beams 5 of the frame. The doors 7 are of such width and length that the inner edges thereof will overlap each other, and the ends of said doors will extend across the lower sides of the end beams 6. The doors 7 are stiffened and strengthened by a pair of longitudinal strips 8 of angle iron, which extend the entire length of the doors near the inner edges thereof. It will thus be seen that the doors 7, when open, will

form a chute by means of which the material being unloaded will be directed between the car rails, and with the doors forming a shield to prevent the rails from becoming obstructed.

The doors 7 are held in closed position by oppositely disposed pairs of links 9, pivotally secured at their lower ends to said doors near the inner edges of, and at a point 65 near the opposite ends thereof. The links 9 have their upper ends pivotally connected to the pivot bolts 10, carried by a pair of slideable bars 11, which are mounted in vertically disposed guide casings 12 having open ends. 70 The casings 12 are mounted centrally on the inner sides of the end walls 4 of the body. The casings 12 are provided with vertical slots 13 on the inner sides thereof for the movement of the pivot bolts 10.

The slideable bars 11 are provided, on the outer sides thereof, with a series of notches 14, adapted to coact with a pair of latches 15 mounted on the outer sides of the end beams 6. The end walls 4 of the body are 80 provided with openings 16 for the passage of the latches therethrough for engagement with the notched sides of the bars 11.

A pair of leaf springs 17 are secured at one end to the outer faces of the end beams 85 6 by the fastening elements 18, the free ends of said springs engaging the outer sides of the latches 15 for the purpose of forcing same inwardly into engagement with the bars 11. The springs 17 are kept under tension by the retaining straps 19 which flex the central portions of said springs inwardly, as will be apparent from a study of the drawings.

A pair of actuating rods 20 having broad, 95 flat inner end portions 21 interposed between the upper portions of the latches 15 and the end beams 6 are rotatably mounted on said end beams. The outer ends of the rods 20 project outwardly beyond the side walls of the car body 1 and terminate in downwardly turned end portions 22. The portions 22 are pivotally connected, at the lower ends thereof, to the opposite ends of an upwardly bowed longitudinally extending transmission rod 23.

The body 1 is mounted upon a pair of axles 24 which pass transversely therethrough at a point intermediate the upper and lower ends of the vertical side walls 2. 110 The axles 24 pass through the side beams 5. Bearing boxes 25 are mounted on the side

beams for the axles 24. The opposite ends of the axles project outwardly from the bearing boxes 25 and have secured thereon the wheels 26. It will thus be seen that, by reason of 5 the axles passing through the body instead of beneath same, said body can be built much deeper, with a corresponding increase in capacity without increasing the height thereof.

10 A closing mechanism is provided for the doors 7 and comprises a shaft 27 which extends transversely through the body 1 above said doors, and is journaled in the side beams 5. One end of the shaft 27 projects outwardly beyond the side of the car and has secured thereto the curved actuating lever 28. Centrally of the car body, the shaft 27 is provided with a crank portion 29 to which one end of a pair of chains 30 is attached, 20 the opposite ends of each of said chains being secured to one of the doors 7.

A trip member 31 is positioned adjacent one side of the track rails 32 in such manner that same will engage the down turned portion 22 of the rods 20 when the car reaches 25 that point. Adjacent the opposite side of the track, a trip 33, adapted to engage the lever 28, is mounted.

The operation of my dump car is as follows:

When the car reaches the point where it is desired to discharge the contents thereof, the portion 22 of one of the actuating rods 20 engages the trip 31 and is swung rearwardly, thereby rotating said rod. Corresponding motion is transmitted to the actuating rod on the opposite end of the car by the bowed rod 23. When the rods 20 are rotated, similar movement is imparted to the flattened end portions 21 thereof with the result that the latches 15 are shifted outwardly against the springs 17, thereby releasing the notched bars 11, as clearly shown in Figure 7. The bars 11 having been released, the doors 7 will then open downwardly and discharge the contents of the car between the track rails. Any tendency of the doors to remain closed will be overcome by the weight of said contents. When the pivot bolt 10 engages the lower end wall of the slot 13, it will serve as a stop to limit the downward swing of the doors.

As the car continues along the track, the upturned end of the lever 28 strikes the trip 33 forcing said lever downwardly and imparting a rotary movement to the shaft 27 which rocks the crank portion 29 of said shaft upwardly. By means of the connecting chains 30 the doors 7 will be drawn upwardly, into the closed position. The upward movement of the doors elevates the notched bars 11 in the casings 12 by means of the links 9. The notches 14 on the bars 11 are of such shape that the latches 15 will ride over same during the upward

movement of said bars, but will prevent any downward movement of said bars unless the latches are withdrawn by the actuating rods 20.

It is thought that the many advantages of a dump car constructed in accordance with this invention will be readily understood, and although the preferred embodiment of the invention is as illustrated and described it is to be understood that changes in the details of construction may be made which will fall within the scope of the appended claims.

What I claim is:

1. A dump car comprising a body provided with supporting wheels, hinged doors forming the floor of said body, casings mounted on said body, slidable bars positioned in said casings and connected to said doors, shiftable latches carried by the car and adapted to co-act with said bars to retain the doors in raised position, and means for shifting said latches toward or away from said bars to latch and release said doors.

2. A dump car comprising a body provided with supporting wheels, a supporting frame secured to said body, hinged doors forming the floor of the body, casings mounted on the opposite ends of the body, said body being provided with openings communicating with the interior of said casings, notched bars slidably enclosed in said casings, connecting links pivotally secured at the upper ends thereof to the bars and at their lower ends to the doors, shiftable latches mounted on the supporting frame, said latches, bars and links constituting means for supporting the doors in raised position, and means for shifting the latches toward or away from the bars to latch and release the doors.

3. A dump car comprising a body having a supporting frame and wheels, hinged doors forming the floor of said body, vertically disposed open ended casings, having slots in the inner sides thereof, mounted on the end walls of the body, said end walls being provided with openings communicating with the casings, notched bars slidably mounted in the casings and having pivot pins projecting therefrom through the slots in said casings, links pivotally mounted at their upper ends on the pivot bolts and at the lower ends thereof to the doors, shiftable latches mounted on the frame and adapted to co-act with the bars for supporting the doors in raised position, and means for shifting said latches toward or away from said bars to latch and release the doors.

4. A dump car comprising a body having a supporting frame and wheels, hinged doors forming the floor of said body, means for supporting said doors in raised position

comprising vertically slideable notched bars connected to the doors and shiftable latches adapted to engage said bars for holding same in raised position, and means for disengaging the latches from the bars comprising actuating rods rotatably mounted on the frame and provided with angularly disposed outer end portions, said rods being further provided with inner end portions

adapted to engage the latches and shift same away from the notched bars, to release the doors and a longitudinally extending rod having its opposite ends connected to said end portions.

In testimony whereof, I affix my signature hereto.

HOMER G. MAHAN.
